UNITED STATES PATENT OFFICE

156,494

COMBINED HEATER AND ELECTRIC FAN

Edward A. Farr, Columbus, Ind., assignor to
Noblitt-Sparks Industries, Inc., Columbus, Ind.,
a corporation of Indiana

Application July 7, 1949, Serial No. 3,765

Term of patent 7 years

(Cl. D26—7)

To all whom it may concern:

Be it known that I, Edward A. Farr, a citizen of the United States, residing at Columbus, Bartholomew County, Indiana, have invented a new, original, and ornamental Design for a Combined Heater and Electric Fan, of which the following is a specification, reference being had to the accompanying drawings, forming part thereof.

Figs. 1, 2, and 3 are, respectively, a front elevation, a side elevation, and a rear elevation of a combined heater and electric fan, embodying my new design; and Fig. 4 is a plan view of the device.

I claim:

The ornamental design for a combined heater and electric fan, as shown.

EDWARD A. FARR.
